NEEDLE ACTUATING MECHANISM FOR
CIRCULAR KNITTING MACHINES

Rudolph E. Zeruneth, Philadelphia, Pa.

Application October 27, 1948, Serial No. 56,756

16 Claims. (Cl. 66—25)

1

This invention relates to circular knitting machinery and more particularly to means for increasing the fabric production of the rotary cam and stationary cylinder type of rib machines.

It is an object of this invention to provide a machine which, for a given cylinder diameter, will have a greater number of knitting feeds on the cam ring thereof than heretofore and will consequently have a greater fabric production.

It is a further object to provide simplified means for moving the cylinder and/or dial cams at each knitting feed of a rib machine whereby the space occupied by each feed may be reduced and whereby additional knitting feeds may be placed upon a given diameter machine.

It is a further object to provide cam moving means including a cylindrically shaped member of relatively small diameter having at one end thereof a longitudinally extending eccentric pin and at its opposite end a pair of diametrically spaced longitudinally extending eccentric pins each spaced equidistantly from the central axis of the member. The cam moving means further includes for one use thereof a cam supporting post adapted to move vertically lengthwise thereof in a suitable bearing in the cylinder cam ring and having a transverse cross head slot in the rear face with a needle actuating cylinder cam secured to the front face thereof, the post being adapted to cooperate with the cylindrically shaped member mounted radially in the cylinder cam ring and rotatable therein, the single eccentric pin projecting into the cross head slot while the two eccentric pins project from the outer face of the cam ring so that, under suitable pattern control, the outwardly projecting pins may be actuated to turn the cylindrical member and cause the desired cylinder cam immediately associated therewith to be moved. For still another use of the cam moving means it includes a link member secured at one end thereof to a movable dial cam and having a pin receiving hole in its opposite end to cooperate with the cylindrically shaped member when the latter is mounted vertically for rotation in a suitable bearing on the cam ring, the single eccentric pin being then fitted in the link member hole with the two eccentric pins projecting from the bearing so that, under suitable pattern control, the latter pins may be actuated to turn the cylindrical member and cause the desired dial cam to be moved.

With these and other objects in view, this invention consists in certain novel features of construction, combination and arrangement of parts

2

to be hereinafter more fully described and claimed.

For a complete understanding of the invention, reference is to be had to the following description and accompanying drawings.

Figure 1 is a plan view of a circular revolving cam ring rib knitting machine with ten knitting feeds shown thereon;

Figure 2 is an enlarged plan view of sections 10 of the revolving cam ring of Figure 1 and a plan view of the pattern control mechanism;

Figure 3 is a view in elevation of the inside 15 of the cam ring sections and pattern control mechanism shown in Figure 2 as viewed from the center of the machine;

Figure 4 is a view in elevation of the outside of the cam ring sections and pattern mechanism shown in Figure 2 as viewed toward the center of the machine;

Figure 5 is a view in section through the cam ring and pattern mechanism, taken along the line 5—5 of Figure 2;

Figure 6 is a detail perspective view showing a cam post and cylindrical actuating member;

Figure 7 is a detail perspective view showing closely adjacent cam posts with cylinder cams secured thereto and a cylindrical actuating member for one of them; and

Figure 8 is an enlarged view showing the dual 30 pin end of the cylindrical actuating member and the means for rotating the said member from its position shown in full line into its position shown in dotted line.

In rib knitting machines having a cylinder and a dial, as compared to plain jersey machines having a cylinder only, the fabric production has generally been much less due to the lesser number of knitting feeds on the rib machines. It has been possible to have more feeds on the jersey machine, and consequently greater production, due to the absence of the dial and attendant needles and cams, and due to the general simplicity of the cams required for jersey knitting. In rib machines, however, of the plain rib or of the interlock or other type of rib knitting, as constructed heretofore and prior to the present invention, the space required for knitting, the more complicated cams and the controls therefor, have all combined to limit the number of feeds that may be conveniently employed, the feeds on a circular rib machine of conventional construction being relatively small in number as compared with those of a jersey machine of comparable size. One of the principal reasons for this is the type of star wheel

55

cam control heretofore used to move the cams on the rib machines, these star wheels taking up so much room as to permit, for example, only four feeds on a machine having an 18 inch diameter needle cylinder, the limited number of feeds resulting, of course, in low production. To increase production by increasing the number of feeds required the construction of a larger diameter needle cylinder machine, but such large diameter machine, while capable of producing fabric at a greater rate was subject to the inherent disadvantage that it necessarily produced a circular fabric of inconveniently and uneconomically large diameter, because such larger diameter fabric would have to be cut to size and seamed for use as a tubular body member in the production of clothing, an obviously undesirable procedure.

However, with the type of cam controls provided by the present invention, a minimum of space is required for the cam moving means and consequently each knitting feed requires much less room with the result that more feeds may be placed upon a given diameter machine than was possible with the star wheel type of cam control. For example, the 18 inch machine above referred to may now have eight feeds thereon, thereby doubling the machine production and at the same time producing a circular knit fabric of a diameter convenient to be used without the objectionable cutting and seaming necessary with the larger size knitted tube. Obviously a smaller diameter machine producing fabric of a convenient diameter at a rate equal to a larger diameter machine, which has heretofore been necessary for this rate of production of an inconvenient size product, is highly desirable and the present invention provides such a machine.

Figure 1 is a plan view of a portion of a rib knitting machine and shows posts 10 extending upwardly from the top flat face of the usual gear ring, not shown, to which the cam ring is secured and which is driven thereby. At the upper ends of the posts 10 is secured a spider arm 11 which in turn supports a center arm 12, the spider arm 11 and the posts 12 providing a support for the needle dial, cams, stop motion, yarns and the normal superstructure of a rib knitting machine, all in the usual manner. The dial cam ring is also driven by suitable connection (not shown) to the posts 12.

Supported on and secured to the gear ring between the posts 10 are cam ring sections 13, here shown as ten in number with two sections between adjacent posts 10. Obviously, the number of cam sections 13 and posts 10 may vary depending upon the diameter of the machine. A dial cam ring is shown at 14 and this contains the usual dial needle operating cams, some of which are movable as shown at 15. There is a set of movable dial cams 15 for each section 13 of the cylinder dial cam ring.

A pattern mechanism 16 is shown at one side of the machine, such mechanism being relatively stationary with respect to the rotating cam ring sections 13, so that as the latter pass the pattern mechanism they may be controlled by it to move the cams in the cylinder and dial cam rings.

Referring now to Figures 2, 3 and 4 where an enlarged section 13 and portions of adjoining sections 13 are shown, it will be seen that each cam ring section 13 is shaped in the form of an arc of a circle and carries a number of cylinder needle actuating cams upon its inner face. Among these cams, secured fixedly to the inner face of a section 13, are cams 17, 18, 19 and 20 all acting upon

the cylinder needles in the making of rib fabric. A movable stitch cam 21 is provided at each feed or section 13 and this is adjustable vertically to lengthen or shorten the stitch by the usual mechanism indicated generally at 22. A star wheel 23 lying in a horizontal plane and forming a part of the mechanism 22 is actuated by an appropriate pattern mechanism, not shown, to cause the stitch cam 21 to move vertically. Movement of the star wheel 23 also causes a post 24, also part of mechanism 22, to turn and this turning post, which is connected by suitable linkage to the dial stitch cam, moves the latter so that the cylinder and dial stitches are adjusted concurrently.

The remaining cams in each cam ring section 13 are movable vertically by the special means forming part of this invention. Referring now to the cam designated at 25, it will be noted that this cam is secured (see Figure 7) to a cylindrical cam post 26 having a vertical groove 27 in a flattened face thereof, by any suitable means, as for example, by a tongue which fits into the groove 27 and which is held therein by a suitable screw. Formed in the opposite flattened face of the cam post 26 is a transversely extending cross head slot 28, such slot being located at different levels on different cam posts.

The two cams designated 29 and 30 are movable and are secured in a similar manner to a similar and adjacent cam post 26. These two cams move together as their supporting cam post 26 is raised or lowered. It will be noted that cam 30 is a thin cam which lies behind an undercut portion of the cam 25. These thin cams act in the usual manner upon long and short butt cylinder needles.

The cam designated 31 is secured to its cam post 26 in a similar manner and is movable therewith. It will be noted that there is a cam 31 for the center cam section 13 shown in these views, but not for the other cam sections. This is conventional inasmuch as the cam 31 is not employed in the knitting at each feed, but performs a needle control action for a complete revolution of the machine on all the needles when it is thrown into action between sections of the fabric.

Each of the cam sections is of solid metal and is provided, on its inner side, with an undercut section 32 having a circumferentially curved inner surface to which the fixed cams are secured. A ledge 33 extends over the undercut section 32, the inner face of this ledge being in close proximity to the needle cylinder when the cam sections are in place. Each cam post 26 has a bearing in the cam sections 13, this bearing being provided by a hole drilled in the cam section near the inner face thereof and passing through the ledge 33, the undercut section 32 and a further undercut section 34, below the section 32. The position of this hole is such that it is complete in the ledge 33, as at 35, and is open at one side thereof in the undercut area 32, as at 36, and is opened to a greater extent at the same side thereof in the undercut area 34, as at 37. The enclosed portions of the cam post 26 bearing hole is sufficient to retain the same therein, while the openings permit the cams to be fastened to the cam posts in position in the cam sections 13. The rear face of the cams fastened to the cam posts 26, e. g. cam 29, face against the undercut surface 32 and keep the cam posts 26 from turning.

In accordance with the present invention, special means are provided for axially moving the

cam posts 26 within the cam sections, said means comprising cylindrical or rod-like members shown at 38, each of relatively small diameter compared to the length thereof and having an off center or eccentrically disposed pin 39 extending longitudinally from one end and a pair of off center, diametrically spaced pins 40 and 41 extending longitudinally from the other end thereof. The pins 39, 40 and 41 all extend parallel to the longitudinal axis of their supporting body member 38, the pins 40 and 41 being spaced equidistantly to either side of the longitudinal axis of said member. Also provided in the member 38 is a centrally located circumferentially extending retaining groove 42 having a pair of diametrically opposed depressions or sockets 43 formed therein. Radial bores are provided in the cam ring sections 13 into which the members 38 rotatably fit, as clearly appears in Figures 2, 3, 4 and 5, the bores being positioned at different levels and at various points in the cam ring section 13 so that they are respectively directly in line with the several movable cam posts 26. Each member 38 is held within its own bearing by means of a spring pressed detent ball 44 suitably mounted in the cam section and which projects into the groove 42 as the member 38 rotates and which also extends into the sockets 43 as a stop means when the member 38 has completed its rotation through an arc of 180 degrees.

Each member 38 when in operative position has the forward eccentric pin 39 thereof fitted within the cross head slot 28 of its associated cam post 26 and has the rear eccentric pins 40 and 41 projecting freely from the outer face of the cam sections 13. At rest, the forward eccentric pin 39 of each member 38 is either in its uppermost or lowermost position, while the outwardly projecting rear eccentric pins 40 and 41 are in one or the other of the positions shown in Figure 8. When the pins 40 and 41 are in the position shown in full lines at the left of Figure 8, then the pin 39 is in its lowermost position and the associated cam post 26 with its attendant cam or cams are in lowered position. Conversely, when the pins 40 and 41 are in their dotted line position shown to the right of Figure 8, then the pin 39 is in its uppermost position and the associated cam post 26 with its attendant cam or cams are in raised position. The movement imparted to each cam post is equal to twice the distance from the center of the cylindrical member 38 to the center of pin 39.

Means are provided to turn each of the cylindrical members 38 a distance of 180 degrees whenever it is desired to move certain of the knitting cams. During the knitting of rib fabric it is at times desirable to change the character thereof, as from plain rib to interlock rib, or it may be desirable to change the stitch structure in other ways. In order to accomplish this, certain of the cams in the cylinder and dial must be moved under pattern control and to this end the mechanism indicated at 16 is provided.

Spaced brackets 45 and 46 are secured to any suitable stationary part of the machine frame and these support between them a shaft 47 and a bar 48, below the shaft 47. At intervals along the shaft 47, corresponding to the circumferential spacing between adjacent members 38 in a single cam section, are journaled a plurality of bell crank levers 49 of which the lower rearwardly extending arms 50 are all of the same length to overlie the bar 48, the number of said cranks corresponding to the number of the members 38.

to be actuated. The upwardly extending arms of the cranks 49, indicated at 51, are of different lengths, each terminating in a rearwardly projecting intercepting finger 52 disposed at the level of a corresponding member 38 within a cam section 13. Accordingly, it will be noted that each member 38 within each cam ring section 13 has an individual actuating member 49 therefor which controls only that member 38. When such an actuating member 49 is in its operative full line position of Figure 5, the intercepting finger 52 thereof lies in the path of one of the pins 40 or 41, as appears in Figure 8, as the same ring rotates past the pattern control mechanism. The upper edge of the finger 52 is positionally coincident with or slightly below the axial center line of the cylindrical member 38 and as the machine rotates the side face of the intercepting finger 52 is engaged by one of the pins, say 40, as in the full line position of Figure 8, so that upon continued rotation of the machine the member 38 is caused to be turned through 180 degrees into the dotted line position shown in this figure, whereupon engagement between the pin 40 and projection 52 ceases, leaving the pins in reversed position. The next time it is desired to move the member 38, the pin 41 will engage the intercepting finger 52 and in a similar manner the member 38 will be again rotated through an arc of 180 degrees to present it in its original position.

The bell crank levers 49 are moved to active position by means of individual pattern pins 53 mounted for limited movement vertically in the bar 48. Each pin 53 underlies the end 50 of a bell crank lever and as a pin is raised the corresponding lever is moved to active position. Conversely, as a pin is lowered the actuating lever 49 is rendered inactive.

The mechanism for shifting the pins 53 selectively as required include a pattern chain 54 on a sprocket 55 which indexes and which also shifts bodily upwardly and downwardly into one or the other of the two positions indicated in full and dotted lines in Figure 5. Appropriate laterally spaced pattern lugs 56 are affixed to cross members of the chain 54 in accordance with the pattern control of the movable cams desired, and as the chain is raised these lugs 56 raise the pins 53 to initiate the action above described. In this manner by placing the lugs 56 on the pattern chain as desired, it is possible to selectively rotate the various members 38 to shift their associated cams and change the character of the rib knitting in accordance with the pattern set up on the chain. It is to be noted that with the intercepting fingers 52 at various levels corresponding to the level of the various members 38, each finger 52 actuates only that particular member 38 which is at the operating level of an intercepting finger.

The movable cams 15 in the dial cam 14 are moved concurrently with the movable cylinder cams, and to accomplish this cylindrical members similar to those designated at 38 in the cylinder cam ring are provided. These cylindrical members are designated 57, here shown as four in number for each feed, and are arranged vertically within a suitable housing 58 secured to each cam ring section 13. In this case the single forward eccentric pin 59 extends upwardly above the upper face of the housing 58, while the two rear eccentric pins 60 and 61 extend downwardly below the housing. Links shown at 62, one for each member 57, extend between the pins 59 and the dial cams 15, being pivotally connected to the latter. The dial cams are pivotally mounted and

as the links 62 are moved substantially radially of the machine, the cams 15 are correspondingly shifted about their own pivot points.

The outer ends of the four links are each provided with a hole within which an eccentric pin 59 is adapted to fit and to rotate. When the pins 59 are in the full line position of Figure 5 the links are in their outermost radial position and conversely, when the pins are in the dotted line position, the links are in their innermost radial position. A spring pressed detent ball 63 suitably mounted in the housing 58 acts on each member 57 in the same manner that the spring pressed detent ball 44 cooperates with the member 38.

To actuate the depending pins 60 and 61, projecting pattern controlled fingers, similar to the fingers 52, are provided. These are shown as the terminal ends 65 of the bell crank levers 64, all of which are also pivoted on the shaft 47 of the pattern mechanism and actuated by appropriate lugs 56 on the pattern chain acting on vertically shiftable pattern pins 53 respectively provided for the several levers 64. In Figure 5, a bell crank lever 64 is shown in dotted lines and the projecting end 65 thereof is positioned to clear the underside of the housing 58 at the point where the pins 60 and 61 extend downwardly. This projecting finger 65 is positioned, when pattern actuated, to engage and intercept only the outermost pin, e. g. pin 60, as the cam ring rotates to turn the member 57 through an arc of 180 degrees in a manner similar to the turning of each member 38 by its operatively associated intercepting finger 52. The next turning of the member 57 would then be by means of contact between the intercepting finger 65 and pin 61, which latter will have assumed the position previously occupied by the pin 60.

It will be noted that at each feed the four members 57 are positioned in the housing 58 at different radial positions with respect to their associated cam ring section 13 and that the upwardly projecting intercepting fingers 65 of the four corresponding levers 64 are also at different radial positions, each of the members 57 and its intercepting finger 65 being at the same radial position so that relative rotation of the cam ring and pattern mechanism causes each member 57 to be actuated only by its own intercepting finger 65. In this manner each of the four dial cams 15 may be separately controlled by the pattern mechanism for desired movement thereof in unison or individually. The four fingers 65, once set by the pattern mechanism, usually for not less than a complete revolution of the machine, will successively engage or not engage the depending pins according to pattern on all of the ten feeds of the machine as they travel past the pattern mechanism.

It will be seen that this invention provides extremely simple and compact means for controlling the positions of the movable cams in the cylinder and in the dial. It will also be seen that due to the simplicity and compactness of the cam control means that a minimum of space is required for all the cams for a single feed and that consequently a greater number of feeds with attendant increased production may be provided for a given diameter of machine than heretofore has been possible.

Referring to Figure 3 it will be noted at 66—66 that the forward ends of two members 38—38 having the pins 39—39 are shown without cam 75

posts or cams associated therewith. In this instance the cam posts and cams have been removed in the interest of clarity to show the appearance of the forward ends of the actuating members 38 in the cam ring section as viewed from the center of the machine.

It will be understood, of course, that the present invention is susceptible of various changes and modifications which may be made from time to time without departing from the general principles or real spirit thereof, and it is accordingly intended to claim the same broadly, as well as specifically, as indicated by the appended claims.

15 What is claimed as new and useful is:

1. In a circular knitting machine of the type having a rotary cam ring and a movable cam associated therewith, means adapted to move said cam comprising a cylindrically shaped member rotatably journaled on the cam ring for actuating said cam, said member having an eccentric pin extending longitudinally from one end and a pair of diametrically spaced eccentric pins extending longitudinally from the opposite end thereof, said latter pair of pins being spaced equidistantly to either side of the longitudinal axis of said member.

2. In a circular knitting machine of the type having a rotary cam ring and a movable cam associated therewith, means adapted to move said cam comprising a cylindrically shaped member rotatably journaled on the cam ring for actuating said cam, said member having an eccentric pin extending longitudinally from one end and a pair of diametrically spaced eccentric pins extending longitudinally from the opposite end thereof, said latter pair of pins being spaced equidistantly to either side of the longitudinal axis of said member, and all of said pins being axially parallel to each other and to the axis of said member.

3. In a circular knitting machine of the type having a rotary cam ring and a movable cam associated therewith, means adapted to move said cam comprising a rod-like member rotatably journaled on the cam ring, said member having a single offset pin extending longitudinally from one end face and a pair of diametrically spaced offset pins extending longitudinally from the other end face thereof, said single pin being operatively related to the said cam and said pair of pins being selectively adapted to rotate the said member through an arc of 180 degrees.

4. In a circular rib knitting machine of the type having a rotary cam ring, a plurality of knitting feeds thereon and movable cams at each feed, means for increasing the feeds for a given diameter of machine comprising cam-shifting devices each occupying a relatively small area of the cam ring, said cam-shifting devices being each in the form of a cylindrical member of relatively small diameter rotatably journaled on the cylinder cam ring, said member having a single offset pin extending longitudinally from one end of said member and a pair of diametrically spaced offset pins extending longitudinally from the opposite end thereof, each of said single pins being operatively related to a movable cam and each of said pair of pins being adapted to rotate the member from which they extend.

5. In a circular knitting machine of the type having a rotary cam ring and a movable cam therein, means adapted to move said cam comprising a cylindrically shaped member rotatable in a cam ring supported housing and extending

therethrough from face to face of the housing, said member having an offset single pin extending longitudinally from one end thereof and a pair of diametrically spaced offset pins extending longitudinally from the other end thereof, said single pin and said pair of pins extending respectively outwardly from opposite faces of said housing, said single pin being operatively related to the said cam and said pair of pins being selectively adapted to rotate the said member in said housing through successive arcs of 180 degrees each.

6. In a circular knitting machine of the type having a rotary cam ring and a movable cam therein, means adapted to move said cam comprising a vertically movable post in the cam ring adjacent the inner face thereof and supporting the said cam, and a cylindrically shaped member rotatable in the cam ring and extending radially therethrough from the rear of the cam post to the outer face thereof, said member having an offset pin extending from one end operatively related to said cam post and a pair of diametrically spaced offset pins extending from the other end thereof and projecting freely from the outer face of the cam ring, said pair of pins being selectively adapted to rotate the said member through successive arcs of 180 degrees, each such rotation of the said member causing the said post and cam to be moved vertically.

7. In a knitting machine having a cam or the like to be moved, a motion transmitting means comprising a housing having opposite faces, a cylindrically shaped member rotatable in said housing and extending therethrough from face to face thereof, an eccentrically disposed single pin extending from one end of said member and a pair of diametrically spaced pins extending from the opposite end thereof, said single pin projecting outwardly from one face of said housing and being operatively related to said cam and said pair of pins projecting outwardly from the opposite face of said housing and being adapted to rotate said member.

8. In a knitting machine having a cam or the like to be moved, a motion transmitting means comprising a housing having opposite faces, a cylindrically shaped member rotatable in said housing and extending therethrough from face to face thereof, an eccentrically disposed single pin extending from one end of said member and a pair of diametrically spaced pins extending from the opposite end thereof, said single pin projecting outwardly from one face of said housing and being operatively related to said cam and said pair of pins projecting outwardly from the opposite face of said housing and being adapted to rotate said member, said pair of pins being spaced equidistantly from the longitudinal axis of said rotatable member and being commonly disposed in a diametric plane of said member angularly related to the diametric plane thereof in which is disposed said single pin.

9. In a circular knitting machine of the type having a rotary cam ring and a movable cam therein, means adapted to move said cam comprising a post vertically movable in the cam ring adjacent the inner face thereof with one face of the post exposed, said cam being secured to the exposed face of the post, a transversely extending slot in the rear face of said post, and a cylindrically shaped member rotatable in the cam ring and extending radially therethrough from the rear of the cam post to the outer face thereof, said member having an eccentrically disposed pin

extending from the inner end thereof into the said slot and a pair of spaced diametrically disposed pins extending from the outer end of said member projecting from the cam ring, said pins being adapted to rotate the said member, rotation of the said member causing the said post and cam to be moved vertically.

10. In a circular knitting machine of the type having a rotary cam ring and a movable cam therein, means adapted to move said cam comprising a post vertically movable in the cam ring adjacent the inner face thereof with one side of the post exposed, said cam being secured to the post at said exposed side, a transversely extending slot in the rear side of said post, a cylindrically shaped member rotatable in the cam ring and extending radially therethrough from the rear of the cam post to the outer face thereof, said member having an eccentrically disposed pin extending from the inner end thereof into the said slot and a pair of spaced diametrically disposed pins extending from the outer end of said member and projecting freely from the cam ring, said pins being adapted to rotate the said member, said member being provided with a circumferential groove having diametric sockets therein, and a spring pressed detent projecting into said slot and adapted to seat in one or the other of said sockets.

11. In a circular rib knitting machine having rotary cylinder and dial cam rings, a movable cam in said dial cam ring, means adapted to move said cam comprising a support mounted on the cylinder cam ring and having upper and lower faces, and a cylindrically shaped member rotatable in said support, and extending vertically therethrough from face to face thereof, an eccentrically disposed pin extending from the upper end of said member and projecting freely above the upper face of said support, a link operatively relating the said pin and the said cam, a pair of spaced diametrically disposed pins extending from the lower end of said member and projecting freely below the lower face of said support in the path of pattern controlled actuating means therefor, said pins being adapted to rotate said member when said actuating means are operatively to effect movement of said link and said cam.

12. A circular rib knitting machine of the type having a plurality of rotary cam ring sections each affording at least one feed, a plurality of movable cams on each cam ring section, means adapted to move each of said cams selectively comprising for each movable cam a vertically movable transversely slotted post mounted in the cam ring section adjacent the inner face thereof with one side of the post exposed, a cam secured to each post at said exposed side thereof, and a plurality of cylindrically shaped members each rotatable in the cam ring and extending radially therethrough from the rear of each post at the level of the transverse slot therein to the outer face of the cam ring, each of said members having an eccentrically disposed pin extending from the inner end thereof into the slot of its associated post and a pair of spaced diametrically disposed pins extending from the outer end of each of said members and projecting from the cam ring, said paired pins on each member being adapted to rotate that member, and stationary pattern controlled actuating means operatively disposed relatively to the paired pins of said members to selectively actuate the latter in accordance with the pattern set up as the cam ring moves past the patterns means.

13. In a circular rib knitting machine of the type having rotary cylinder and dial cam rings and a number of feeds thereon, a plurality of movable cams at each dial feed, means adapted to move each of said cams selectively comprising at each feed a support mounted on the cylinder cam ring and having upper and lower faces, a plurality of cylindrically shaped members rotatable in said support and extending vertically therethrough from face to face thereof, said members being positioned with their axes substantially parallel to each other and along a line intersecting the circumference of said cylinder cam ring so that each is a different radial distance from the center of the machine, an eccentrically disposed pin extending from the upper end of each of said members and projecting above the upper face of said support, a plurality of links operatively relating said pins to said movable dial cams, a pair of diametrically spaced pins extending from the lower end of each of said members and projecting freely below the lower face of said support at points spaced the said different radial distances from the center of the machine, and stationary pattern controlled actuating means disposed at each of said radially spaced points to selectively actuate each of said pairs of pins in accordance with the pattern set up as the cam rings move past the pattern means.

14. In a knitting machine having a cam or the like to be moved, a motion transmitting means comprising a support having opposite faces, a cylindrically shaped member rotatable in said support and extending therethrough from face to face thereof, an eccentrically disposed single pin extending from one end of said member and a pair of diametrically spaced eccentrically disposed pins extending from the opposite end thereof, said single pin projecting outwardly from one face of said support and being operatively related to said cam and said pair of pins projecting outwardly from the opposite face of said support and being adapted to rotate said member, and pattern controlled means selectively operative to engage each of said pair of pins for successively rotating said member through arcs of 180 degrees upon each such engagement, each 180 degree rotation of the said member causing the single pin to move the said cam a distance equal to twice the distance between the center of said member and said single pin.

15. In a knitting machine having a cam or the like to be moved, a motion transmitting means comprising a support having opposite faces, a cylindrically shaped member rotatable in said housing and extending therethrough from face to face thereof, an eccentrically disposed pin extending

5 from one end of said member and a pair of diametrically spaced eccentrically disposed pins extending from the opposite end thereof, all of said pins being parallel to each other and to the longitudinal axis of the cylindrical member and lying within the extended cylindrical surface of the member, said single pin projecting outwardly from one face of said support and being operatively related to said cam and said pair of pins projecting outwardly from the opposite face of said support and being alternately engageable to successively rotate said member through arcs of 180 degrees.

16. In a circular knitting machine of the type having a sectionalized rotary cam ring the several sections of which are respectively provided with cams, certain of said cams being movably mounted to permit them to be alternately set into one of several positions, means for setting said movable cams alternately into one of their several positions, said means including a rotatable cam-setting member rotatably carried by said cam ring with its axis generally transverse of the direction in which each movable cam is adapted to be moved when moved from one of its positions to another of its positions, means intermediate said cam-setting member and a movable cam for operatively interconnecting the same so as to set said movable cam into a predetermined position corresponding to each position of said cam-setting member, tooth means carried by said rotatable cam-setting member whereby said cam-setting member may be rotated, successively, fractions of a revolution to its several setting positions, and an intercepting selector abutment carried by said knitting machine at a predeterminedly fixed locus relatively to said cam ring and movable generally radially with respect to said ring for engaging one of the teeth of said tooth means of said rotatable cam-setting member as the latter moves with its cam ring through the orbit of rotation of the latter.

RUDOLPH E. ZERUNEITH.
